CLAIM

The ornamental design for the edging scissors, as shown and described.

DESCRIPTION

FIG. 1 is a perspective view of an edging scissors showing our new design;

FIG. 2 is a front elevational view thereof;

FIG. 3 is a rear elevational view thereof;

FIG. 4 is a top plan view thereof, the bottom view being identical thereto;

FIG. 5 is a left side elevational view thereof; and,

FIG. 6 is a right side elevational view thereof.

The broken line showing of the blades is for illustrative purposes only and forms no part of the claimed design.
